UNITED STATES PATENT OFFICE.

ROBERT M. CATLIN, OF FRANKLIN, NEW JERSEY, ASSIGNOR TO CATLIN SHALE PRODUCTS COMPANY, OF WILMINGTON, DELAWARE, A CORPORATION OF DELAWARE.

APPARATUS FOR THE TREATMENT OF SHALE OR THE LIKE.

1,272,377.

Specification of Letters Patent. Patented July 16, 1918.

Application filed August 9, 1917. Serial No. 185,244.

To all whom it may concern:

Be it known that I, ROBERT M. CATLIN, a citizen of the United States, residing at Franklin, county of Sussex, and State of New Jersey, have invented certain new and useful Improvements in Apparatus for the Treatment of Shale or the like, fully described and represented in the following specification and the accompanying drawings, forming a part of the same.

This invention relates to improvements in apparatus for the treatment of materials such as bituminous shale.

It is an object of the invention to provide apparatus including a retort, or the like, in which material such as shale may be treated, such that the material is conveyed through the retort without any clogging and so as to make possible an increased product.

It is a further object of the invention to provide an apparatus having provision for adjusting the amount of material supplied to the retort or the like.

The following specification describes and the accompanying drawing illustrates apparatus constructed in accordance with the invention, it being understood that changes may be made in the form, construction and arrangement of the parts without departing from the invention, the form herein disclosed being a preferred embodiment thereof.

The drawing shows a view partly in vertical section and partly in side elevation of apparatus constructed in accordance with the invention.

Referring to the drawing, bituminous shale or other material to be treated, is placed, properly crushed, in a hopper 15 having in its bottom an outlet in which seats a conical valve 16 secured to a rod 17 operated in any suitable manner to open and close the valve. When the valve is open, the material drops into a feed tank 18 into which extends a number of tube like retorts 19. In the present embodiment, there are four of these retorts of which two appear in the drawing, the other two being in the same planes as those shown. In that portion of each retort which extends into the feed tanks, is a receiving port 20 for the reception of the material being treated. The four retorts 19 pass through a furnace 21 comprising walls 22 and floor 23 of firebrick and supported by a base 24. As will be ap-

parent from the drawing, the retorts slant 55 upward from the receiving end toward the discharge end.

The invention includes means for supplying heat to the furnace, thereby to heat the retorts. Although capable of various constructions, in the present embodiment, beneath the furnace 21 is a grate or fuel chamber 25 having an end opening 26 for the introduction of fuel and a plurality of top openings 27 communicating with the furnace 60 21. The furnace is covered with a roof 28 provided with a number of openings 128 for the escape of the waste gases. When a suitable fuel is burned in the grate the hot gases pass up through the openings 27 into the 65 furnace and on up around the retorts, passing out by the escape ports 128, providing the required heat for the retorts. As shown the furnace is adapted for oil burning, and openings 27 diffuse the oil blast.

The invention includes means for conveying the shale or other material through the retorts from the lower receiving end to the higher delivery end and in structures embodying the invention to the best advantage the feed is so designed that the material is fed forward faster and is spread out in a thinner mass as it approaches the delivery end of the retorts. This may be accomplished, for example, by mechanism comprising a shaft having means associated therewith for increasing the speed of feed and for gradually spreading or thinning out the mass as it moves through the retort. Although capable of various constructions, in 90 the form shown, journaled in bearings 30 supported by brackets 31 on the side of the feed tank, and in bearings 32 supported by a yoke 33 at the delivery end of the apparatus, are shafts 34, each shaft being 95 enclosed in a retort. On the end of each shaft, at the delivery end, is a gear 35, all four meshing with a central master gear 36 mounted on a stud 37 journaled in the yoke 33. On this stud is also mounted a ratchet 100 38 driven in any suitable manner to drive the four conveyor shafts through the stud and the master gear 36. As shown, the other ends of the shafts are provided with gears 39, the members of the upper and lower 105 pairs being respectively in mesh. Each conveyor shaft 34 is provided with a helical blade 40, the pitch of which varies, being

greater at the delivery end. As illustrated, this increase of pitch is gradual from the receiving end of the conveyer to the delivery end. With such a construction, for a given constant speed of revolution of the conveyer shaft, the material being fed is moved forward faster as it approaches the delivery end of the retort and at the same time it is spread out in a gradually thinning mass, thus, clogging is prevented and the material is made available for a thorough treatment which serves to drive off substantially all of the volatile constituents, and an increased production is obtained.

15 At the delivery end, the conveyers empty through a discharge pipe 44 for delivering the spent products to a suitable water supply for quenching the same and for sealing the pipe to prevent the admission of air to the retorts. For the delivery of the uncondensed vapors and gases, a pipe 41 is tapped into the upper part of the feed tank. Another pipe 42, tapped into the lower portion of the feed tank, serves to carry away 25 the evolved oils, which run or trickle down the inclined retorts and pass into the tank 18 via openings 43.

The invention includes means for regulating the amount of material received by a 30 retort and in structures embodying the invention to the best advantage, there is provided, in each retort, a receiving port, the available size of which may be adjusted. Although capable of various constructions, 35 in the form shown, that portion of each retort which extends into the feed tank is a separate sleeve, rotatable in the bearing bracket 31 and in a similar bracket 46, a complementary bracket 47 serving to support the end of the stationary part of the 40 retort at the joint. Formed in this rotatable sleeve is the receiving port 20 heretofore mentioned. By rotating the sleeve, a greater or less portion of the port is positioned to receive material falling from the 45 hopper and so the amount received by the retort for conveyance therethrough is regulated as desired.

It is believed that the operation of the apparatus will be clear without further description.

What is claimed is:

1. In apparatus for the treatment of materials such as shale, a retort, and a conveyer for moving the material through the retort including means for spreading out the material in a thinner mass near the delivery end of the retort.

2. In apparatus for the treatment of ma-

terials such as shale, a retort, and a conveyer for moving the material through the retort including means for spreading out the material in a gradually thinning mass as it approaches the delivery end of the retort.

3. In apparatus for the treatment of materials such as shale, a retort, and a conveyer for moving the material through the retort including means for feeding the material faster near the delivery end.

4. In apparatus for the treatment of materials such as shale, a retort, and a conveyer for moving the material through the retort including means for gradually increasing the speed of the feed.

5. The combination of a retort, and a conveyer, for moving the material to be treated through the retort, having a helical blade of varying pitch.

6. The combination of a retort, and a conveyer, for moving the material to be treated through the retort, having a helical blade greater in pitch at the delivery end than at the receiving end.

7. The combination of a retort, and a conveyer, for moving the material to be treated through the retort, having a helical blade gradually increasing in pitch toward the delivery end.

8. The combination of a retort, a hopper for feeding material to the retort, a receiving port in said retort, and means for adjusting the available size of said port.

9. The combination of a retort, a hopper for feeding material to the retort, and a receiving port in said retort, that portion of the retort in which said port is located being rotatable to adjust the available size of said port.

10. The combination of a retort, a conveyer for moving the material to be treated through the retort, having a helical blade of gradually increasing pitch, and a ratchet for driving said conveyer.

11. The combination of a tubular retort, and a conveyer, for moving the material to be treated through the retort, having a helical blade of varying pitch.

12. The combination of a tubular retort, and a conveyer, for moving the material to be treated through the retort, having a helical blade of varying pitch, said retort being concentric with the conveyer and having a radius slightly larger than that of the conveyer.

In testimony whereof, I have hereunto set my hand.

ROBERT M. CATLIN.
